KNIFE BLADE

Robert F. West, Simsbury, Conn., assignor to The Stanley Works, New Britain, Conn., a corporation of Connecticut

Filed Mar. 8, 1965, Ser. No. 84,132

Term of patent 14 years

(Cl. D22—3)

FIG. 1

FIG. 2

FIG. 3

FIG. 4

FIG. 1 is a front elevational view of a knife blade, showing my new design;

FIG. 2 is a top view of the knife blade of FIG. 1;

FIG. 3 is a back elevational view of the knife blade of FIG. 1; and

FIG. 4 is an end view of the knife blade of FIG. 1.

The characteristic feature of my design resides in the combination on the knife blade of rhomboidal shape as disclosed, of a series of spaced apart scored lines on one face parallel to the ends of the blade, each segment or scored area having an ellipsoidal hole therein at right angles to the cutting edge all as shown.

I claim:

The ornamental design for a knife blade, as shown and described.
